UNITED STATES PATENT OFFICE

WILLIAM M. BAILEY, OF LYNN, MASSACHUSETTS, ASSIGNOR, BY MESNE ASSIGNMENTS,
TO GENERAL ELECTRIC COMPANY, A CORPORATION OF NEW YORK

ELECTRICAL CONDENSER

Application filed December 21, 1927. Serial No. 241,507.

This invention relates to electrical condensers of a type suitable for use with comparatively high power, such as that employed in radio transmitting circuits.

5 A feature of the invention is a condenser for use in comparatively high power circuits and provided with a shield for distributing the static forces which, in the case of high frequency circuits, tend to set up corona dis-
10 charges about the condenser terminals. The condenser is also provided with a safety gap to prevent injury to the various parts when excessive voltages are applied, and is designed and constructed throughout with extreme
15 rigidity and simplicity.

The invention also provides an insulating casing for the condenser and novel means for securing the cover thereto. The casing includes a long surface creepage path between
20 parts of opposite polarity and is shielded from rain.

The invention also consists in certain new and original features of construction and combinations of parts hereinafter set forth
25 and claimed.

Although the novel features which are believed to be characteristic of this invention will be particularly pointed out in the claims appended hereto, the invention itself, as to
30 its objects and advantages, the mode of its operation and the manner of its organization may be better understood by referring to the following description taken in connection with the accompanying drawings forming a
35 part thereof, in which

Fig. 1 is a vertical section of the condenser taken on the line 1—1 of Fig. 2 and looking in the direction of the arrows;

40 Fig. 2 is a bottom plan view of the condenser with the cover partly broken away showing the interior arrangement of the parts; and

45 Fig. 3 is an elevation partly in section of a modified form of condenser provided with contact feet to facilitate series connections.

Like reference characters denote like parts in the several figures of the drawings.

In the following description and in the
50 claims parts will be identified by specific names for convenience, but they are intended

to be as generic in their application to similar parts as the art will permit.

Referring to the drawings more in detail, the invention is shown as applied to a condenser stack S enclosed in a suitable casing 55 which serves as a support for the condenser itself and for the terminal members thereof.

The casing comprises an insulating cup member D which may be formed of molded vitreous material such as isolantite or other suitable insulating material. Secured to said casing D is a base cover element BE provided with an upwardly extending flange AB surrounding the adjacent portion of the casing D and spaced therefrom. The adjacent 60 portions of flange AB and the insulating casing may be provided with grooves TM and TI respectively for cooperating with cement C or other suitable filling material for holding and rigidly securing the elements together. 65 The base element BE is provided with an interior opening across which pressure bar PB is secured. The ends of said bar rest on portions of the base element on opposite sides of said opening and are frictionally held in 70 contact therewith when the stack is assembled.

Pressure screw PS is threaded in pressure bar PB and is utilized for exerting pressure upon pressure plate PP and clamping the 75 condenser stack S between said plate and the bottom of casing D. Stack S may comprise a plurality of units formed of conducting foils and dielectric material in the usual manner and joined together in series relationship 80 as by connection SC. The particular construction of the condenser stack, however, forms no part of the present invention.

Contact plate CP is positioned between the bottom of insulating cup D and stack S in electrical contact with contact strip CS—1 which may be electrically connected to the outer foil of condenser stack S as by connection EC. Terminal stud TS is secured to contact plate CP and extends through a suitable aperture in casing D forming one terminal of the condenser. Connecting strips CS—2 and CS—3 connect the opposite terminal of condenser stack S to base element 85 BE, said strips being passed around flange 90
100

AS of said element and secured thereto as by screws SR.

After the condenser has been securely clamped in place, the space between the condenser stack S and casing D may be filled with suitable insulating filling material F. A metal cover MC may then be secured, as by screws SR, to base element BE for protecting pressure screws PS and preventing accidental turning thereof.

Shield TE may be carried by terminal stud TS and separated from the bottom of casing D as by flexible spacing element LS which may be formed of lead or other suitable material. Shield TE may be secured to member D as by nuts LN and BN threaded upon terminal stud TS cooperating with washer W. Said member TE is preferably cupped, the sides NS extending concentric with and parallel to the cylindrical sides of member D but spaced therefrom.

Member TE, being electrically connected to terminal stud TS, serves to distribute the electrostatic stress and to prevent a corona discharge or breakdown. The shield also operates as a heat radiating member and assists in cooling said terminal stud as well as a rain shield for preventing moisture from forming on cup D. In order to avoid damage due to an excess voltage, a spark gap may be provided as by inserting an electrode E in a suitably tapped hole in member TE and securing the same as by set screw SS. Electrode E is in suitable position to cooperate with flange AB of base element BE and form a spark gap which may be adjusted to break down at any given voltage.

In the modification shown in Fig. 3, the condenser is constructed as above described with the exception of feet FT which are formed on both the base element and the shield. In this case the terminal stud TS is threaded into the shield TE and rigidly secured thereby, the shield itself serving as a terminal for the condenser. The condensers are thus adapted to be arranged in stacked formation in case a plurality of units are to be connected in series.

The type of casing above described provides a long surface distance between opposite terminals and reduces the surface creepage. The rain shield assists in reducing the creepage by insuring a dry surface. The losses are reduced due to the length of dielectric between parts of opposite polarity and the use of only a single cemented ring for closing the casing.

The casing has been described as formed of isolantite, a vitreous material moulded in a plastic state and fired. It is, however, not limited to this material but may comprise glass, porcelain, phenol condensation product or other strong insulating substances.

The provision of feet to facilitate stacking and series connection is especially ad-

vantageous in applying the condenser to commercial conditions. The mechanical support also serves as an electrical connection and reduces the parts required.

While certain novel features of the invention have been shown and described and are pointed out in the annexed claims, it will be understood that various omissions, substitutions and changes in the forms and details of the device illustrated and in its operation may be made by those skilled in the art without departing from the spirit of the invention.

What is claimed is:

1. A stack condenser, an insulating casing therefor, a base element forming a closure for said casing, means for clamping said stack under pressure, contact strips connecting one terminal of said stack with said base element, a terminal element extending through said casing and forming the other terminal of said stack, means for distributing the electrostatic stress thereabout comprising a metallic cupped shield spaced from said casing and an electrode carried by said shield and forming in connection with said base element a safety spark gap.

2. In combination with a condenser stack, an insulating casing having an open end, a closure member for said end, means for cementing said member to said casing, said member constituting one terminal of said stack, the other terminal of said stack extending through said casing, a shield secured thereto for distributing the electrostatic stress, and an electrode carried by said shield and forming with said closure member a safety spark gap.

3. In a stack condenser, a casing therefor having an open end and a closed end, a contact plate electrically connected to one terminal of said stack and interposed between said stack and closed end of said casing, a terminal stud secured to said contact plate and extending through said end, a metallic cover member, means for securing said member to the open end of said casing and means carried by said member for clamping said stack against said contact plate.

4. The combination with an electrical condenser, of a casing of insulating material enclosing said condenser on the sides and one end, a terminal projecting thru said casing at the end of the condenser enclosed by said casing and rigid metallic means spaced from and substantially parallel to the sides and end wall of said casing for mechanically protecting the closed end of said casing.

5. The combination with an electrical condenser, of a casing of insulating material enclosing said condenser on the sides and one end, a terminal projecting thru said casing at the end of the condenser enclosed by said casing and rigid metallic end member connected to said terminal and extending across

the insulating end wall of said casing and around the casing side walls to remove mechanical and electrical stresses from casing end wall.

5 6. An electric condenser comprising a stack of dielectric and armature elements, a casing of structural insulating material having one end closed by the insulating material of said casing to an amount sufficient to require insertion of said stack through the opposite end of the casing, said opposite end of the casing being bridged by a metal member secured thereto, said stack being clamped between said metal member and the closed end of the casing, the end closing portion of the insulating casing transmitting stack clamping stress, a terminal extending out through the closed end of the casing and an opposite stack terminal being connected to said metal member.

7. An electric condenser comprising a stack of dielectric and armature elements, a casing of structural insulating material having one end closed by the insulating material of said casing to an amount sufficient to require insertion of said stack through the opposite end of the casing, said opposite end of the casing being bridged by a metal member secured thereto, said stack being clamped between said metal member and the closed end of the casing, the end closing portion of the insulating casing transmitting stack clamping stress, a terminal extending out through the closed end of the casing and an opposite stack terminal being connected to said metal member, said metal end member being perforate for insertion of said stack, and means bridging the perforate portion of said metal member and transmitting stack clamping stress.

40 8. An electric condenser comprising a stack of dielectric and armature elements, a casing of structural insulating material having one end closed by the insulating material of said casing to an amount sufficient to require insertion of said stack through the opposite end of the casing, said opposite end of the casing being bridged by a metal member secured thereto, said stack being clamped between said metal member and the closed end of the casing, the end closing portion of the insulating casing transmitting stack clamping stress, a terminal extending out through the closed end of the casing and an opposite stack terminal being connected to said metal member, and means for adjusting stack clamping compression on said stack through at least one end of the casing.

In testimony whereof I hereunto affix my signature.

63 WILLIAM M. BAILEY.
